UNITED STATES PATENT OFFICE

133,118

DESIGN FOR A DISPLAY BOX FOR JEWELRY OR THE LIKE

Robert W. More, Madison, Wis.

Application March 5, 1942, Serial No. 106,090

Term of patent 14 years

To all whom it may concern:

Be it known that I, Robert W. More, a citizen of the United States, residing at Madison, in the county of Dane and State of Wisconsin, have invented a new, original, and ornamental Design for a Display Box for Jewelry or the like, of which the following is a specification, reference being had to the accompanying drawing, forming part thereof.

Fig. 1 is a perspective view of a display box for jewelry or the like, showing my design when the box is in opened position;

Fig. 2 is a perspective view of the display box in closed position; and

Fig. 3 is an end elevational view thereof.

I claim:

The ornamental design for a display box for jewelry or the like, as shown.

ROBERT W. MORE.
